UNITED STATES PATENT OFFICE.

ARTHUR W. BURWELL, OF POUGHKEEPSIE, NEW YORK.

PROCESS OF PRODUCING CHROMIC-ACID SOLUTIONS.

No Drawing.

Application filed January 23, 1922. Serial No. 531,282.

To all whom it may concern:

Be it known that I, ARTHUR W. BURWELL, a citizen of the United States, residing at Poughkeepsie, in the county of Dutchess and 5 State of New York, have invented certain new and useful Improvements in Processes of Producing Chromic-Acid Solutions, of which the following is a specification.

In an application filed concurrently here- 10 with, Ser. No. 531,281, I have described and claimed a process of oxidizing chromic salt solutions by causing the same to flow successively through the cathode and anode compartments of an electrolytic cell having 15 a porous diaphragm, employing certain precautions having the effect of insuring a high degree of efficiency in the utilization of the current and a continued normal operation of the process. Thus, in said process I prefer- 20 ably use an anode consisting of cast metal, which may be lead; or a lead-antimony alloy containing a comparatively small proportion —say up to 7 per cent—of antimony; or a lead-antimony alloy presenting an active 25 face of lead. In said process also I use sufficient excess of chromic salt in the flowing electrolyte to avoid substantial evolution of oxygen at the anode. A preferred form of 30 apparatus for use in connection with the above process comprises a containing vessel of lead or lead-antimony alloy serving as the anode; a porous cup or vessel function- 35 ing as a diaphragm; and a cathode, which may be of sheet lead, within the latter.

According to the present invention I am 40 able to prepare directly from chromic hydroxid, a solution of chromic acid substantially free from sulfuric acid. The apparatus employed may be the same as that used for the oxidation of chromic salt solutions 45 as mentioned above; but in the present process it is unnecessary to provide for a continuous flow of solutions.

In practicing the present invention I pro- 45 vide an electrolytic cell having a porous dia- phragm of acid resisting material such as filtros, porous earthenware or the like. Both

electrodes may be of lead, or a lead-anti- 50 mony alloy containing about 3.5-7.0% of antimony as described above, cast metal being preferably used in either case. The solution surrounding the cathode may consist of dilute sulfuric acid, or alternatively of any soluble sulfate. The anode compartment contains initially a suspension or 55 magma of chromic hydroxid in water, slightly acidulated with sulfuric acid, or containing a small addition of a soluble sulfate such as chromic sulfate, sodium sulfate, etc. Upon passage of the electric current 60 the chromic hydroxid is progressively, and eventually completely, oxidized to chromic acid. Preferably the proportion of chromic hydroxid to water in the original charge is such that the concentration of CrO_3 in the 65 final solution will approximate but not exceed 10%. Anode current densities of the order of 18 amperes per square foot are preferred, with cathode current densities of the order of 100-200 amperes; 85-95° C. is a 70 favorable working temperature. The process is most conveniently operated intermittently; but it is within my invention to provide for continuous or semi-continuous operation, the chromic acid solution being 75 withdrawn from the anode compartment, and the equivalent quantities of chromic hydroxid and water supplied thereto.

I claim:

1. Process of producing chromic acid so- 80 lutions which consists in subjecting a magma or suspension comprising chromic hydroxid and water to anodic oxidation.
2. Process according to claim 1 in which the anodes present active surfaces of cast 85 lead.
3. Process according to claim 1 in which the anode consists of a cast alloy of lead and antimony, said alloy containing a relatively 90 small proportion of antimony.

In testimony whereof, I affix my signature.

ARTHUR W. BURWELL.
